CLAIM

The ornamental design for a biker lighter, as shown and described.

DESCRIPTION

FIG. 1 is a perspective view of the biker lighter design shown in full lines, with the broken lines illustrating a linked chain with which the design may be used, but which forms no part of the claimed design;

FIG. 2 is a left side elevational view of the biker lighter of the present invention; the right side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective view thereof showing the design in an open position.
